PORTABLE CUTTING DEVICE

Harry A. Cumfer, South Bend, Ind.; Garnetta Domke, executrix of said Harry A. Cumfer, deceased, assignor of one-third to Lucille Cumfer Hayes, Chicago, Ill., one-third to Edith Cumfer Thompson, Whittier, Calif., one-twelfth to Donald A. Cumfer, Jr., Nashville, Tenn., one-twelfth to Margaret L. Cumfer, South Bend, Ind., one-twelfth to Dionne Cumfer, and one-twelfth to Harry Cumfer, both of Houston, Tex.

Application August 6, 1949, Serial No. 109,030

5 Claims. (Cl. 164—61)

1

This invention relates to improvements in cutting devices for sheet or board material such as asphalt saturated siding, roofing material and the like, and refers particularly to a portable cutting device which may be conveniently transported to the situs of the job and may be employed to cut material to various dimensions and cut the material in various configurations as required to permit the application of the material for its intended purpose.

One of the important objects of the present invention resides in the provision of a device of the character described which is of relatively light weight and of compact construction and yet is rugged and performs its task as a cutting device most conveniently and efficiently.

Another important object of the invention resides in the provision of means for cutting sheet or board material wherein relatively large sized sheets or boards may be cut and wherein, normally difficult interior cuts may be simply and conveniently made.

Other objects and advantages of the present invention will be apparent from the accompanying drawings and following detailed description.

In the drawings,

Fig. 1 is a side elevational view, parts being broken away, and parts being shown in section of my improved portable cutter.

Fig. 2 is a top plan view of the device illustrated in Fig. 1.

Fig. 3 is a transverse sectional view taken on line 3—3 of Fig. 1.

Fig. 4 is a horizontal sectional view taken through the stub shaft housing and through one of the cutter heads.

Fig. 5 is a sectional view taken on the line 5—5 of Fig. 2.

Fig. 6 is a detailed sectional view taken on line 6—6 of Fig. 1.

Referring in detail to the drawing, 1 indicates the main portion of the frame of the portable cutter, the frame comprising essentially lower shaft housing 2 and upper shaft housing 3 joined together at one end by sprocket housing 4. The lower shaft housing 2 carries a supporting boss 5 and also carries a clamp member 6 in which a screw 7 is threadedly positioned, said screw carrying at its upper end an abutment plate 8 and at its opposite end a handle 9 whereby the cutter may be secured to any desired supporting surface 10, the supporting member 10 being confined between the abutment plate 8 and the boss 5. The sprocket housing 4 extends downwardly beneath the lower shaft housing 2 to form a rear support

2

as shown at 11 in Fig. 1 for the device. The shaft housings 2 and 3 adjacent their juncture with the sprocket housing 4 carry webs 12 which function to reinforce and rigidify the structure.

5 The extending end of the shaft housing 3 is enlarged as shown best at 13 in Fig. 6, the enlarged portion 13 being bifurcated to provide two spaced bearing arms 14. A stub shaft housing 15 having an enlarged end 16 is adapted to be received between the bearing arms 14 of the enlarged portion 13 of shaft housing 3. A pair of bolts 17 extend through the bearing arms 14 and are threadedly engaged with the enlarged portion 16 of the stub shaft housing 15.

10 The arrangement is such that the stub shaft housing 15 may be swung through a predetermined angle with respect to the shaft housing 3. As will be hereinafter more fully described this expedient permits the convenient separation of the two cutting knives which constitute the cutting elements of the present device.

15 A shaft 18 extends through the entire length of the lower shaft housing 2, said shaft being journaled adjacent both of its ends. Only one of the bearing supports for the shaft 18 is illustrated and constitutes ball bearing assembly 19 which is carried within a boss 20 formed upon the inner face of the sprocket housing 4. A similar ball bearing assembly may be employed to support the shaft 18 at its opposite end.

20 A shaft 21 is positioned in the upper shaft housing 3, said shaft being journaled in ball bearing assembly 22 which is carried by boss 23 formed on the inner face of the sprocket housing 4.

25 The opposite end of shaft 21 is keyed to a universal joint 24 (Fig. 6) and a spacer member 25 functions to prevent excess axial movement of the shaft 21 within the upper shaft housing 3. A stub shaft 26 is positioned within the stub shaft housing 15 and is keyed at one end to the universal joint 24 which is carried within a housing provided by the enlarged member 16. In normal operation shafts 21 and 26 are in axial alignment with each other and shaft housings 3 and 15 are also in axial alignment with each other. However, when stub shaft housing 15 is swung about the pivot bolts 17 with respect to shaft housing 3 the shafts 21 and 26 will be disposed angularly with respect to each other. As will be herein-
30 after more fully described the shaft 21 comprises a driving shaft and the stub shaft 26 comprises a driven shaft. To permit the stub shaft housing 15 to be swung with respect to the shaft housing 3 the juncture between the two shafts 21 and 26 comprising the universal joint 24 will permit such

swinging motion to occur. It will be noted that the axis of articulation of the universal joint 24 occurs along the axis of the pivot bolts 17.

A sprocket wheel 27 is mounted upon the end of shaft 18 which projects into the sprocket housing 4. An identical sprocket wheel 28 is similarly mounted upon that end of shaft 21 which projects into the sprocket housing. A sprocket chain 29 is trained around both sprocket wheels 27 and 28, said chain being driven by sprocket wheel 30. A closure 31 is removably mounted upon sprocket housing 4 and is secured thereto by means of screws 32. An electric motor 33 is mounted upon the closure 31 and is secured thereto by means of bolts 34. Disposed in operative relationship to the electric motor 33 a gear reducing mechanism of conventional construction 35 is carried adjacent the motor 33. A shaft 36 projects from the gear reducing mechanism 35 into the sprocket housing 4 through opening 37 in closure 31, said shaft carrying and actuating the sprocket wheel 30. In this manner both shafts 18 and 21 are rotated.

Referring particularly to Figs. 4 and 5, the shaft housing 2 is enlarged at its end and is provided with a relatively enlarged bore 38. Similarly the stub shaft housing 15 is enlarged at its end and is provided with a relatively enlarged bore 39. In the enlarged bore 38 a worm 40 is carried upon the end of shaft 18 and in the enlarged bore 39 a worm 41 is carried upon the end of stub shaft 26. The worms 40 and 41 are respectively secured to the shafts 18 and 26 by means of keys 42. At the end of each of the enlarged portions of the shaft housings 2 and 15, a plug 43 is positioned, one plug being threadedly engaged in each of the bores 38 and 39. By the provision of the plugs 43, worms 40 and 41 may be mounted or removed from the respective shafts upon which they are mounted and lubricant may be introduced into the enlarged bore.

A housing 44 comprises an integral portion of the end of the shaft housing 2 adjacent the bore 38. In said housing a shaft 45 is journaled in bearings 46. A worm wheel 47 is carried upon an end of shaft 45 and is adapted to mesh with the worm 40. The worm wheel 47 is non-rotatably secured to shaft 45 by means of key 48 and longitudinal movement of the worm wheel 47 is prevented by means of bolt 49 which engages the end of shaft 45.

Similarly a housing 50 comprises an integral portion of the end of stub shaft housing 15 and a shaft 51 is journaled in a bearing 52 in said housing. A worm wheel 53 is non-rotatably secured to shaft 51 by means of key 54 and a bolt 55 functions to prevent axial movement of the worm wheel.

Closure plates 56 and 57 are secured by screws 58 respectively to the housings 44 and 50.

It will be noted by reference particularly to Figs. 2 and 4 that the shafts 45 and 51 are disposed at an obtuse angle to the shafts 18 and 26, respectively. The purpose of this arrangement will be hereinafter more fully described.

Companion collars 58 and 59 are mounted upon an end of shaft 45 which projects from housing 44. The companion collar 59 is provided with an annular slot 60 in which a circular cutting knife 61 is positioned. The arrangement is such that when the companion collars are mounted upon shaft 45 they form a roll which confines the knife 61 between them rendering said knife relatively immovable with respect to said collars. A

nut 62 threadedly engages the end of shaft 45 and functions to confine the knife 61 under pressure between the companion collars 58 and 59. A semi-circular housing 63 is mounted upon the housing 44 and provides a semi-annular trough 64 through which the lower-half portion of the knife 61 travels. An absorbent material or wicking 65 is positioned in the semi-annular trough 64, said absorbent material, during operation of the device being saturated with water, oil or the like. The knife 61 in passing through the semi-annular housing 64 cuts through the absorbent material 65 and in this manner the surface of the knife 61 is continuously wetted.

Companion collars 66 and 67 are mounted upon an end of shaft 51 which protrudes from housing 50. The collar 67 is provided with an annular slot 68 which is adapted to receive a circular cutting knife 69. A nut 70 is threadedly engaged upon the end of shaft 51 and functions to confine the knife 69 between the companion collars 66 and 67.

A semi-circular member 70 is mounted upon the upper portion of housing 50, said member being provided with a semi-annular trough 71 which is adapted to carry a quantity of absorbent material 72. The upper portion of the semi-circular member 70 is provided with an opening 73 (Fig. 2) which connects with the semi-annular trough 71. The absorbent material 72 is adapted to be saturated with water, oil or the like which may be introduced into the semi-annular trough through the opening 73. The knife 69 at the upper half of its travel cuts through the absorbent material 72 carried in the trough 71 and in this manner the cutting surface of said knife is continuously wetted.

When the device is in operative position the cutting heads comprising the housings 44 and 50 and the knives 61 and 69 together with their respective retaining members, are disposed adjacent each other in such fashion that the straight or unbevelled portions of the knives are disposed adjacent each other as shown best in Fig. 5. It will be noted that the surfaces of companion collar 58 and companion collar 67 are provided with annular grooves 74 and 75, respectively. The length of the cutting portion of each of the knives is such that when the knives are disposed in cutting position the cutting edges of the knives 61 and 69, respectively, enter the grooves 75 and 74. During the cutting operation the surfaces of the collars 58, 59, 66 and 67 bear with pressure upon the surface of the material being cut which tends to densify the material being cut along the lines of incision. In this manner a neat, clean cut is effected and the material adjacent the cut edges being densified, tends to prevent the entrance of water or moisture during use. When cutting asphalt saturated board, for example, the edged portions are not only densified but portions of the asphalt are smeared by the bevelled portions of the knives over the cut edges, tending to form an edge seal.

A pair of spaced lugs 76 is mounted upon the upper portion of the stub shaft housing 15. A lug 77 is mounted upon the enlarged end of shaft housing 3. A bifurcated bell crank lever 78 is pivotally secured by means of pivot pin 79 to lug 77. One arm of the bell crank lever 78 carries a handle 80 and the opposite arm thereof is pivotally connected to a link 81 by means of pivot pin 82. The opposite end of link 81 is pivotally connected to the spaced lugs 76 by means of pivot pin 83.

A lug 84 is carried upon the bottom portion

of the stub shaft housing 15, said lug being apertured to receive the end of bolt 85, said bolt being slidably positioned in said lug. The opposite end of the bolt 85 is bifurcated and is pivotally connected to lug 86 carried at the end of the shaft housing 3 by means of pivot pin 87. A compression coil spring 88 embraces the bolt 85 between its pivotal connection to lug 86 and lug 84.

The arrangement is such that under normal circumstances spring 88 tends to rock the stub shaft housing 15 and the cutting head carried thereon about the pivot bolts 17, the motion being counterclockwise as viewed in Fig. 1. To lower the cutting head to operative cutting position, handle 80 is moved in a clockwise direction as viewed in Fig. 1 about the pivot 79. In so swinging the handle 80 the bell crank lever 78 moves the stub shaft housing downwardly through the agency of link 81 against the compressive force of spring 88. This movement continues until the cutting heads are in operative cutting position as shown in Fig. 5 at which time one arm of the bell crank lever 78 and the link 81 are disposed substantially in dead center 25 position or slightly below dead center position. A stop 89 is formed upon stub shaft housing 15 and functions to limit the clockwise movement of the bell crank lever 78.

In utilizing my invention, the device may be mounted as hereinbefore described upon any suitable support by means of the clamping arrangement comprising the screw 7 and lug 5. With the absorbent wickings 65 and 72 thoroughly saturated with water, oil or the like, the material to be cut, that is the asphalt saturated siding, roofing or the like, is positioned above the lowermost knife 61 with the upper cutting head in upraised position. The line of cut may previously have been inscribed upon the material to be cut and with said line disposed in proper relationship to the lowermost knife, motor 33 may be set into operation and by the manipulation of handle 80, that is the movement thereof in a clockwise direction as viewed in Fig. 1, the upper cutting head may be lowered to operative cutting position, the toggle mechanism associated with the handle 80 functioning to lock the upper cutting head in its cutting position. The cut may then conveniently be made, a portion of the cut material straddling the spaces between the opposed cutting heads and the sprocket housing 4. It will be noted that by disposing the cutting heads at an obtuse angle to their respective drive shafts 18 and 26, a portion of the material to be cut will pass between the cutting heads and the sprocket housing 4 at an angle and consequently I have found this to be the most convenient disposition of the cutting heads.

Of course, it is to be understood that the cutting heads may be disposed at substantially any angle with respect to the shafts 18 and 26, respectively. However, in general, it is believed that the angular disposition of the cutting heads provides the greatest flexibility of use.

It is desirable before lowering the upper cutting head to cutting position that the motor be set into operation so that the load may be placed on the motor more or less gradually. In addition, by the provision of the swingable upper cutting head, interior cuts may be most conveniently made, the handle 80 being manipulated to start and stop the cutting operation. In this fashion, square or triangular or rectangu-

lar openings may be cut in the interior of the area of the board and by the proper manipulation of the board during the cutting operation, arcuate lines of cut may also be made within the area of the board.

In view of the fact that this device is particularly applicable to the cutting of materials which are saturated with asphalt, the provision for wetting the knives proves most convenient and makes the cutting operation easier to perform. However, it is to be understood that my device, although particularly adaptable for cutting saturated board or roofing can be employed to cut any type of fibrous material, plastic material or even thin gauge metals.

In order to conveniently move and carry my portable cutter, a handle 127 may be carried upon the upper shaft housing 3 of the form of my invention illustrated in Figs. 1 to 6, inclusive.

It will be understood by those skilled in the art that many modifications of my invention may be made without departing from the spirit thereof, and consequently I do not wish to be limited except as necessitated by the prior art.

I claim as my invention:

1. A portable cutting device comprising in combination, a frame comprising two spaced arms, a cutting head carried by each arm, one of said arms being pivoted intermediate its length to move said cutting heads toward and away from each other, means for rotating said cutting heads, each cutting head comprising a circular cutting knife, means for locking said pivoted arm with the knives of said cutting head in shearing relation to each other, and means intermediate of and on one of said arms for moving that part of said pivoted arm which carries the cutting head away from the other arm to permit disposition of material to be cut between said cutting heads.

2. A portable cutting device comprising in combination, a frame comprising two spaced arms, a cutting head carried by each arm, one of said arms being pivoted intermediate its length to move said cutting heads toward and away from each other, means for rotating said cutting heads, each cutting head comprising a circular cutting knife, toggle means for locking said pivoted arm with the knives of said cutting head in shearing relation to each other, and means intermediate of and on one of said arms for moving that part of said pivoted arm which carries the cutting head away from the other arm to permit disposition of material to be cut between said cutting heads.

3. A portable cutting device comprising in combination, a frame comprising two spaced arms, a cutting head carried by each arm, one of said arms being pivoted intermediate its length to move said cutting heads toward and away from each other, means for rotating said cutting heads, each cutting head comprising a circular cutting knife, toggle means for locking said pivoted arm with the knives of said cutting head in shearing relation to each other, means intermediate of and on one of said arms for moving that part of said pivoted arm which carries the cutting head away from the other arm to permit disposition of material to be cut between said cutting heads, and resilient means for holding said arms in separated relationship with respect to each other.

4. A cutting device comprising in combination, a frame comprising two spaced arms, a cutting head carried by each arm, means for rotating said cutting heads one of said arms being pivoted intermediate its length to move said cutting heads

toward and away from each other, said means comprising a shaft carried by each arm and operatively connected to each cutting head a universal joint carried intermediate the length of the shaft carried by the pivoted arm to permit swingable movement of the shaft with the arm, and means carried by said frame for driving said shafts to rotate said cutting heads, each cutting head comprising a circular cutting knife, means for positioning those portions of said arms which carry said cutting heads relative to each other to dispose the cutting knives in shearing relation to each other, and means intermediate of and on one of said arms for separating said cutting heads with respect to each other to dispose therebetween material to be cut.

5. A cutting device comprising in combination, a frame comprising two spaced arms, a cutting head carried by each arm, means for rotating said cutting heads, said means comprising a shaft carried by each arm and operatively connected to each cutting head a universal joint disposed intermediate the length of one shaft, the arm carrying said last mentioned shaft being pivoted to permit simultaneous swingable movement of said arm and shaft, and means carried by said frame for driving said shafts to rotate said cut-

10
